UNITED STATES PATENT OFFICE.

WALTER J. DUDLEY, OF EVERETT, MASSACHUSETTS, ASSIGNOR TO THE DUDLEY ELECTRIC MANUFACTURING COMPANY, OF CONCORD, N. H.

TELEPHONE SIGNALING APPARATUS.

SPECIFICATION forming part of Letters Patent No. 295,913, dated April 1, 1884.

Application filed June 19, 1883. (No model.)

To all whom it may concern:

Be it known that I, WALTER J. DUDLEY, of Everett, in the county of Middlesex and State of Massachusetts, have invented certain

5 Improvements in Telephone Signaling Apparatus, of which the following is a specification.

This apparatus belongs to that class of electrical signaling apparatus in which a series of electrical impulses operate switching devices 10 step by step, said devices co-operating with a lever actuated by a supplemental armature in a manner to be described. Devices for preserving unison are provided; also, devices peculiar to this apparatus for preventing any 15 variation of line-resistance while step-by-step devices are operative; also, devices for allowing a bell to be rung by ordinary alternating magneto-current when circuited by this apparatus without disturbance to said apparatus, 20 all of which I will now proceed to describe.

Of the accompanying drawings, forming a part of this specification, Figure 1 represents a front elevation of an apparatus embodying my improvements, and a diagram of the electrical connections. Fig. 2 represents a side elevation of the same. Fig. 3 represents a 25 top plan view. Fig. 4 represents an enlarged bottom plan view. Figs. 5, 6, 7, 8, 9, and 10 represent detail views showing different parts 30 of the operation.

The same letters of reference indicate the same parts in all the figures.

In the drawings, C represents an electro-magnet, supported by a frame composed, in 35 this instance, of two permanent magnets, $a' a'$, and a bracket or cross-piece, b, secured to the inner sides of said magnets, but magnetically insulated therefrom by copper washers $c c$, interposed between the bracket b and magnets 40 $a' a'$.

A B represent polarized armatures pivoted at $i i$ to the ends of the permanent magnets $a' a'$, and so polarized that their free ends are of like sign, so that they are simultaneously 45 attracted or repelled by the electro-magnet, each armature being composed of two arms, 2 2, connected by a cross-bar, 3. I prefer to make said arms and cross-bar 3 in each armature of a single piece of iron, the cross-bar 50 being much thinner than the arms 2 2, to di-

minish the short-circuiting capacity of said cross-bars. This construction is more economical than a composite armature with a cross-bar of brass or like metal connecting the arms 2.

55

j represents the arbor of the index-finger k.

a represents a step-by-step ratchet on the arbor j.

l represents a lever attached to the polarized armature A, and provided at its lower end with arms $m m$, having pallets $m' m'$, adapted to alternately come in contact with the ratchet a when the lever l is oscillated and rotate said ratchet and its arbor step by step. The lever l is oscillated by the intermittent 60 currents sent through the electro-magnet and by the force of a retracting-spring, o, which draws its free end away from the poles of the electro-magnet.

To the armature B is attached a lever, D, 70 weighted by means of an adjustable weight, B', on an arm, p, attached to said lever. The armature B is arranged to remain indifferently wherever left by the last current—that is to say, either in contact with the poles of 75 the electro-magnet or away from the same.

The lever D, actuated by the armature B, carries upon its free end the following devices, 80

viz:

First. A cut-out spring, d, arranged, when the armature B is attracted, to make contact with a screw, d', which is supported by but electrically insulated from the metal frame of the instrument, and is connected by wire 4 with the line out, as shown in Fig. 1. When 85 such contact is made, all the telephonic apparatus at the station where the instrument is placed is short-circuited.

Secondly. A bell cut-out consisting of a spring, e, normally in contact with a metal 90 contact-point, e', supported by but insulated from the lever D, and connected by wire 5 with the magneto-generator 6 of the station and with line out, thereby short-circuiting the magneto-bell 7.

Thirdly. A projection, f, arranged to be moved into or out of the path of a similar projection, f', on ratchet-wheel a, to preserve unison.

Fourthly. A spring-catch, g, co-operating 100

with a pin, h' , in a disk, h , on the arbor j , to limit the play of the armature B , and thereby prevent it from being brought into permanent contact with the electro-magnet C whenever the bell 7 , governed by the apparatus, is operative.

Fifthly. A spring, i , co-operating with the disk h and with the spring e , to render the armature B sensitive to slight attractive currents.

The ratchet-wheel a is provided with a pin, r , which is adapted once during each rotation of the arbor j to form a stop for the spring e , and separate the latter from its contact e' when the armature B is repelled and its lever D is thrown inwardly, as hereinafter described.

Operation: It will be convenient to call a current of the proper direction or polarity to attract the armatures an "attractive current" and its opposite a "repellent current." In the normal state of the apparatus, with the line unoccupied and the indicator-hand on zero, both armatures will be away from the electro-magnet, and a repellent current would, if sent to line, take the following path in any one apparatus: to binding-post 8 , through the coils of the electro-magnet to the frame of the instrument, spring e , its contact e' , wire s , post 9 , through the office telephone apparatus, except the bell, and on to the next office. Thus it is evident the bell 7 is out of circuit. Now, if a subscriber at the station in question call the exchange by a crank-magneto, the armature A will be unaffected, as its spring is too strong to be overcome by such weak currents; but armature B , being lightly poised, is affected, and means must be provided to prevent it from making a permanent contact with its electro-magnet C , or else the calling station would cut itself out on the first turn of its magneto. To this end the projection f on the armature-lever D and the co-operating projection f' on the ratchet-wheel a are employed, the latter being located outside of the former when the pointer k is at zero, so that the armature B cannot make contact with the electro-magnet, its play being limited by the projection f' , as shown in Fig. 5.

If an attractive current be sent to line, and in the office under consideration subscriber has his telephone T circuited, the extra resistance might make the current too weak to operate armature A ; but it would operate armature B , which, in the condition last described, has sufficient play to allow spring d to make yielding contact with screw d' . The current immediately has a new path, as follows: to post 8 , magnet C , frame of instrument, spring d , screw d' , wire 4 , and on to next office. Thus the whole telephonic resistance is cut out, the current attains full strength, armature A is attracted, moving wheel a step by step, the projection f' becomes disengaged from projection f , allowing armature B to make contact with electro-magnet C , where it sticks while the necessary number of attractive impulses are sent to rotate wheel a to the office-number.

At this point a repellent current is sent, causing armature B to separate from the electro-magnet, and of course breaking the connection between d and d' , and as at this time the pin r in wheel a is under the end of spring e , the movement of armature-lever D causes said pin to engage said spring and break its contact with e' , as shown in Fig. 6, thereby circuiting the bell, which is then rung by a magneto-current. The restoration to the zero-point at the conclusion of a message is effected by a number of attractive followed by a repellent impulse, the armature B being held to the poles of the magnet by the attractive impulses, and thus holding its projection f in the path of the projection f' until the former arrests the latter, as shown in Fig. 7, the pointer being then nearly at zero, and the armature of lever l attracted to the electro-magnet, the pallets m being in position to give the ratchet-wheel a forward step. The repellent impulse is then given, causing the armatures A and B and their levers to assume the positions shown in Fig. 5, the projection f releasing the projection f' , so that the armature A , in moving away from the electro-magnet under the influence of the retractile spring, gives the ratchet a step forward, and thus brings the pointer to unison.

It is quite important to prevent the armature B from sticking to the electro-magnet (through the magneto-currents) at the called office. To this end the catch g , co-operating with pin h' in disk h at the office-number, is provided. Said catch engages the pin h' , as shown in Fig. 3, when the office-number is reached. By said pin the play of the armature B is limited as at the zero-point, and as the mass of the armature B and its attachments is quite large, and its movements quite slow in comparison with those of the armature of a magneto-bell, the momentary contacts between d and d' do not affect the bell.

The weight B' must be located far enough away from lever D to overcome the tension of the spring e when the latter is engaged by the pin r on the wheel a ; but when said spring is disengaged the weight B' is excessive and prevents the armature B from responding to weak currents. I therefore provide the spring i , which, by striking the periphery of the disk h , becomes the equivalent of spring e , being prevented from acting simultaneously with the same by a notch, h'' , in said disk, in which an offset, i' , on said spring plays, as shown in Fig. 9, when spring e is engaged by the pin r in wheel a . The armature B is thus enabled to respond to comparatively weak as well as to stronger currents.

It will be borne in mind that the pin h' on the disk h will be differently located in each instrument in the circuit, so that it will engage the catch g at only one station at a time.

The projection f is beveled on the side which is adjacent to the pin f' when the parts are in the position shown in Fig. 5, so that when the lever D is moved outwardly by the next at-

tractive impulse through the electro-magnet the beveled side of the projection *f*, striking the pin *f'*, will not impede the rotation of the ratchet-wheel, but will have a wedge or cam like action on said pin, facilitating the rotation of the ratchet.

v represents a spring which bears with a yielding pressure against one end of the arbor *j*, and acts as a brake to prevent the arbor 10 from being rotated more than one step at a time, this action being due not only to the direct bearing of the spring on the end of the arbor, but also to the endwise pressure imparted to the arbor by the spring, which presses a shoulder, 15 *v'*, on the arbor against a bearing, *w*, which may, if desired, be a yielding spring-plate interposed between said shoulder and a fixed surface. (See Fig. 10.) The spring may be adjusted to vary its pressure on the arbor by 20 means of a screw, *w'*.

I claim—

1. In a telephone signaling apparatus, the combination of an electro-magnet, two polarized armatures, A B, provided with operating-levers and adapted to be simultaneously attracted and repelled, the armature A being provided with a retractile spring and the other being poised lightly, an arbor adapted to be rotated step by step by the lever of armature 25 A, and switching devices, substantially as described, operated by the lever of armature B, whereby, when the instruments are at unison and repellent currents are sent to line, the bell of the station or office where the instrument 30 is located is thrown out of circuit, as set forth.

2. The combination of an electro-magnet, the polarized armatures A B and their operating-levers, the arbor adapted to be rotated step by step, as described, means whereby the 35 armature B is prevented from making contact with the electro-magnet when the central office is being called, and switching devices operated by the lever of armature B, whereby the entire telephonic resistance at 40 the calling station is cut out and the full strength of the current is applied to rotating the arbor to the office-number, as set forth.

3. The combination of an electro-magnet, the polarized armatures A B and their operating-levers, an insulated contact-point and a 45

spring therefor on the lever of armature B, normally short-circuiting the bell at the station where the apparatus is located, the arbor adapted to be rotated step by step, as described, and provided with a stop or pin 55 adapted to separate said spring from its contact-point, and thereby circuit the bell and permit the latter to be rung by a magneto-current, as set forth.

4. The combination of an electro-magnet, 60 the polarized armatures A B and their operating-levers *l* and *D*, the latter having a projection, *f*, the arbor adapted to be rotated step by step, and provided with a pin, *f'*, adapted to co-operate with the projection *f* 65 and arrest the arbor near the zero-point, as set forth.

5. The combination of an electro-magnet, the polarized armatures A B and their operating-levers, the arbor adapted to be rotated 70 step by step, and means whereby the movement of the armature B and its lever is arrested when the arbor is rotated to the office-number, as set forth.

6. The combination of the arbor rotated 75 step by step, as described, and provided with the pin *r* and notched disk *h*, and the weighted armature-lever *D*, provided with the springs *e* and *i*, adapted to act, respectively, on the pin *r* and the periphery of the disk *h*, whereby the 80 influence of the weight of the armature-lever is partially counteracted and the armature is enabled to respond to weak currents, as set forth.

7. The combination, with the step-by-step- 85 rotated arbor *j*, having a shoulder, *v'*, of the spring *v*, bearing against the end of said arbor, and pressing the shoulder thereof against a bearing-surface, as set forth.

8. The combination, with the arbor *j* and 90 its adjusting-spring *v*, of means for varying the pressure of said spring, as set forth.

In testimony whereof I have signed my name to this specification, in the presence of two subscribing witnesses, this 6th day of June, 1883.

WALTER J. DUDLEY.
